UNITED STATES PATENT OFFICE.

HERRICK AIKEN, OF FRANKLIN, NEW HAMPSHIRE, ASSIGNOR TO CHARLES L. AIKEN,
OF FRANKLIN, NEW HAMPSHIRE.

ELECTRICALLY-OPERATED KNITTING-MACHINE.

1,273,802.

Specification of Letters Patent. Patented July 30, 1918.

Application filed March 14, 1917. Serial No. 154,719.

To all whom it may concern:

Be it known that I, HERRICK AIKEN, of Franklin, in the county of Merrimack and State of New Hampshire, have invented certain new and useful Improvements in Electrically-Operated Knitting-Machines, of which the following is a specification.

This invention relates to knitting machines, and my invention refers particularly to a simplified means or method of operating such machines, not to any special details of the knitting machine itself.

Many circular knitting machines as now constructed employ individual electric motors for running them, with different gearing connections for operating the different parts of the machine. The construction is usually such that the motor is located at the lower part of the machine, and the power is carried up to the head of the machine, eventually driving the cam cylinder when the machine is of the type having a stationary needle cylinder.

The object of my invention is to provide means for simplifying the construction and operation of circular knitting machines, by mounting the electric motor on the head of the machine, with the magnets of the rotating element of the motor carried directly by the needle cylinder or the cam cylinder according to whether one cylinder or the other is to be rotated, and then carrying the power down therefrom to operate other parts of the machine such as the pattern mechanism.

To this end my invention consists in the construction substantially as hereinafter described and claimed.

Of the accompanying drawings:

Figure 1 is a sectional elevation of so much of a knitting machine embodying my invention as is necessary to illustrate the same.

Fig. 2 is a plan view of the same.

Similar reference characters indicate similar parts or features in both views.

The machine to which my improvements are applied may be of any circular type other than that illustrated. In the drawings I intentionally omit all details other than those necessary to illustrate one embodiment of my invention. In said drawings, the top plate of the knitting machine is indicated at 12, said plate having a circular flange 13 to support the cam cylinder 14.

Mounted on the top plate is a ring 15 within which are the field magnets 16. Suitable connections of the wiring of said magnets are made with binding posts 17 indicated in Fig. 2. An annular plate 18, which may be of suitable insulating material, is supported by ring 15 and covers the space for the field magnets. The armature members 19 are suitably connected to the cam cylinder 14 to drive the same. Also secured to the cam cylinder is a ring 20 for the commutator sections 21, the brushes 23 for which (Fig. 2) are carried by blocks 22 mounted on the cover plate 18.

The motor may be of series wound type or shunt wound type, or universal type, employing either direct or alternating current.

The lower edge of the cam cylinder 14 is formed or provided with a circular series of gear teeth 24 meshing with a gear wheel 25 loosely mounted on, or secured to, a suitably mounted shaft 26.

The needle cylinder 27 is supported in stationary position by a plurality of arms 28 one of which is shown in Fig. 1, said arms being rigidly connected with a flange 29 of top plate 12 and extending under the gear ring 24.

It will be understood that when the current for the motor is on, the cam cylinder will be rotated to reciprocate the needles in the usual manner, and that the teeth 24 will rotate gear wheel 25 from which power may be taken by any suitable gearing and connections to operate other parts of the machine, instead of driving the cam cylinder by means of gear members 25, 24. This will be readily understood by reference to Letters Patent 1,052,877, granted February 11, 1913, to A. N. Ames, and to parts particularly illustrated in Figs. 5, 6, 8 and 34 thereof, especially the latter figure. In said patent a gear ring 2, which is connected with cam cylinder 1 to rotate the latter is in mesh with a compound gear 4, 4^a mounted loosely on stud shaft 5, said gear meshing with a gear 6. If now it be assumed that the gear wheel 25 of the accompanying drawings is like gear 4, 4^a of said patent, and in mesh with another gear such as gear 6 of the patent, much of the mechanism of said patent below gear 4, 4^a will be driven. As it would in no way aid in understanding my present invention to explain the operation of such

lower mechanism, I believe it to be unnecessary to go into the details thereof.

Having now described my invention in one of its embodiments, although without attempting to illustrate or describe all of the modifications or variations thereof, or all modes of use, what I claim is:

1. A knitting machine having an electric motor for operating it, the rotary element of the motor being carried by a rotary element of the machine itself at its head, means being provided for operating other elements of the knitting machine below its head by power obtained from the electrically driven element of the knitting machine.
2. A knitting machine having a stationary needle cylinder, a rotatable ring surrounding said needle cylinder and having armature magnets, and field magnets to operate with the armature magnets, the inner face of said ring being formed as a cam to actuate the needles, whereby said ring

constitutes a combined cam cylinder and armature magnet carrier.

3. A knitting machine having a rotary cam cylinder, and an electric motor therefor, the armature members of the motor being directly connected to said cam cylinder to rotate it.

4. A knitting machine having a rotary cam cylinder, and an electric motor therefor, the armature construction of the motor surrounding the cam cylinder and connected thereto to rotate it.

5. A knitting machine having a rotary cam cylinder, and an electric motor therefor, the armature construction of the motor being connected to said cam cylinder to rotate it, gearing for operating other parts of the knitting machine being connected with said cylinder.

In testimony whereof I have affixed my signature.

HERRICK AIKEN.
